PRINTING DEVICE

Edwin Kirk Large, Atlanta, Ga.

Application January 24, 1934, Serial No. 708,119

4 Claims. (Cl. 101—96)

This invention relates to printing devices and it has particular relation to that type of machine used in connection with card and index systems for filling, recording, etc.

One object of the invention is the provision of a compact printing mechanism comprising a series of discs, in this instance of irregular shape, bearing printing type at their lower peripheries and being provided with indicia at their upper peripheries whereby an operator may easily and quickly set the mechanism.

Another object of the invention is the provision, in a mechanism of this character, of one or a plurality of standard ribbons whereby one or a plurality of copies may be made simultaneously of a particular printing.

Another object of the invention is the provision of means whereby, after the type has been set, reprints may be made as many times as the operator desires without resetting the type.

For a better understanding of the invention reference will now be had to the accompanying drawings forming part of this disclosure wherein:

Figure 1 is a top plan view of a printing mechanism involving the novel features of the invention;

Figure 2 is a front elevational view of the device with the cover removed;

Figure 3 is a side elevational view of the device as shown in Fig. 2;

Figure 4 is a side elevational view of a portion of the device showing details of construction;

Figure 5 is a sectional view taken substantially along the line 5—5 of Fig. 2;

Figure 6 is an enlarged sectional view taken substantially along the line 6—6 of Fig. 4.

Figure 7 is a side elevational view of a disc having a portion of its radius reduced; and

Figure 8 is a fragmentary view of a similar disc but having its radius reduced to a more limited extent.

The embodiment of the invention illustrated in the accompanying drawings comprises a base portion generally designated at 10 having fastened thereto a pair of upright frame members 11 which carry a cylindrical bearing 12 extending for a distance through one of the members 11. Projecting through the bearing 12 is a main shaft 13 having at one of its ends an operating handle 14 and carrying at its other end a cam 15 formed with a reduced portion 16 and positioned in an opening 17 in a cam plate 18. The plate 18 is linked to a bell crank lever 19, as indicated at 20, within the base 10 and the lever is pivoted upon a shaft 19 carried by depending lugs 21

attached to the base 10. The lever 17 carries upon its other end a pressure plate 22 and is yieldingly held in an elevated position by means of a spring 23, one end of which is fastened to the base 10, as shown at 24, and the other end bears against a cut-out portion of the lever 17, as indicated at 25. The lever 17 is held in its proper plane within the base by means of trunnions 26 formed integral with the lever 17 and encompassing the shaft 19.

Revolutely mounted upon that portion of the bearing member 12 which lies between the upright members 11 is a sleeve 27 carrying a pair of upwardly projecting integral levers 28 having pivoted at their outer extremities, as indicated at 29, a pair of links 30 which are rigidly fastened to a horizontally disposed restoring rod 31. One of the levers 28 carries a lug 32 having fastened thereto and to the base 10 a spring 33 whereby the restoring rod 31 is normally held in its retracted position.

At the end of the projecting portion of the bearing member 12 is provided a pair of lock nuts 34 which hold in position a plurality of discs 35 which are revolutely mounted on the bearing member, each one of which carries at its lower periphery a set of type 36 and at its upper portion an operating handle 37 projecting through a slot 38 in a cover 41. Fastened to the handle 37, as indicated at 39, is a rearwardly projecting arcuate shaped indicia bearing band 40 which is adapted to register with one of the openings 41 in the cover 41. The restoring rod 31 moves through guiding slots 42 in the frame members 11.

One of the frame members 11 is provided with a pair of laterally extending arms 43 which have mounted between their extremities bearing members 44 carrying ribbon spools 45 and 46, carrying concentric ratchets 47 and 48. A pair of pawls 49, pivotally mounted at either end of a slidably mounted plate 50, are positioned to selectively engage the ratchets 46 or 47. The plate 50 is actuated by means of a pin 51 carried by the sleeve 27.

The spools have wound thereon an inked ribbon 52, but it will be understood that if the applicant so desires he may, by the exercise of mechanical skill, utilize a plurality of ribbons mounted similarly to those disclosed whereby a multiplicity of copies may be made instead of a single copy as is shown in the accompanying drawings. The spools are adapted to be adjusted manually by means of knurled knobs or handles 53.

5 A slidably mounted reciprocating link member 54 interconnects a pair of trip members 55 preferably made integral with the pawls 48 and each disengages its pawl when the ribbon on its roller has attained sufficient volume. A pair of 10 guide rollers 57 and 58 are mounted upon the frame members 11 for guiding the ribbon. Carried on the end of the shaft 13 remote from the lock nut 34 is a restoring lever 60 adapted to engage the restoring rod 31. A repeat print lever 61 is pivoted intermediate its ends upon a stud 62 and has one of its ends in coactive relation with the restoring rod 31 as indicated at 63, and carries at its other end an operating handle 7.

15 In Figures 7 and 8 there is shown a modified form of disc having either a large portion of its radius reduced as indicated at 5 or a small portion reduced as indicated at 4. It will be seen that such construction allows for the non-engagement of such discs by the restoring rod 31. This is particularly desirable in the case of discs 20 bearing indicia which would of necessity repeatedly have to be set in the same place but for such construction, as, for example, month and day 25 indicia. It is to be understood that such modified discs are to be utilized in conjunction with those above described.

30 In the operation of the particular embodiment of the invention disclosed by the accompanying drawings a paper, card or the like is first placed beneath the discs 35 through a suitable opening 37. The levers 37 are then pulled downwardly in the slots 22 until the desired indicia on the bands 39 appear in the openings 40. The type 35 on the bands 36 corresponding to such indicia will then be in position directly over the pressure plate 21 with the paper or card and the ribbon 51 interposed.

40 The handle 14 is then rotated in a clockwise direction, thereby first causing a quick upward movement of the pressure plate 21 and accordingly an impression of the type upon the paper and upon further rotation causing the mechanism to return to its original position ready for 45 resetting.

45 The movement of the pressure plate is caused by the cam plate 16 moving downwardly by reason of the registration of the reduced portion 9 of the cam 15 with an irregular portion of the plate 16 surrounding the opening 8. This downward movement is in turn caused by the upward force exerted by the spring 23 against one end of the lever 17, with which, as shown at 18, the cam plate is engaged at the other end.

50 The return of the discs to their original position is caused by further rotation of the handle when the lever 60 causes a downward movement of the rod 31 by engaging the rod and forcing it downwardly through the guide slots 64. This causes the rod to engage the rear portion of the discs 35 turning them clockwise until they have reached what may properly be termed their zero position, whereupon the rod 31 is moved by the guide slots out of the path of the lever 60 and upon the completion of one revolution of the handle 14 the cam 15 will again be in position and the whole mechanism ready for 55 resetting.

55 In case it be desired to repeat a particular printing upon the same or a different card, paper or the like, it is only necessary to move the handle 7 forwardly. This will cause its opposite end to engage the rod 31 and remove it from the path of the lever 60. The remainder of the operation 60 is the same as above described except that the

discs will not be returned to their zero position and upon a complete revolution of the handle 14 the type will remain in position for printing the same characters as in the first operation of the device without the necessity of resetting the type.

5 Although but one form of the invention has been illustrated and that form has been described in detail it will be apparent to those skilled in the art that the invention is not so limited but that various minor modifications may be made therein without departing from the spirit of the invention or the scope of the appended claims.

What is claimed is:

1. A printing device consisting of a base, a pair 15 of supporting members mounted thereon, a drum carried by the supporting members, a plurality of discs revolubly mounted upon the drum and having printing type at their lower peripheries and levers at their upper portions for setting the 20 type in desired position, a spring actuated pressure plate for engaging the positioned type, means for operating the pressure plate including a bell crank lever carrying the plate at one end, a spring tending to force the plate in the direction of the 25 type, a cam plate engaging the other end of the lever and having an irregular opening revolubly positioned within the opening and adapted to allow a sudden movement of the pressure plate when the 30 offset portion coincides with a portion of the opening in the cam plate and a handle for operating the same, and means for restoring the discs to their original position including a bar 35 slidably mounted in the supporting members and adapted to engage portions of the discs and a lever operable by the handle for moving the bar.

2. A printing device consisting of a base, a pair of supporting members mounted thereon, a drum carried by the supporting members, a plurality 40 of discs revolubly mounted upon the drum and having printing type at their lower peripheries and levers at their upper portions for setting the type in desired position, a spring actuated pressure plate for engaging the positioned type, means for operating the pressure plate including a bell crank lever carrying the plate at one end, a spring tending to force the plate in the direction of the 45 type, a cam plate engaging the other end of the lever and having an irregular opening therein, a cam having an offset portion revolubly positioned within the opening and adapted to allow a sudden movement of the pressure plate when the offset portion coincides with a portion of the opening in the cam plate and a handle for operating the 50 same, and means for restoring the discs to their original position including a bar slidably mounted in the supporting members and adapted to engage portions of the discs and a lever operable by the handle for moving the bar and repeat mechanism 55 for rendering the restoring means inoperative including a latch for moving the bar out of the path of the lever and a handle for operating the latch.

3. A printing device consisting of a plurality 60 of revolubly mounted discs having printing type at their lower peripheries and having levers for setting the type in desired position, a spring actuated pressure plate, means operable by a handle for releasing the plate against the positioned type, and a bar simultaneously operable by the handle 70 to engage the discs to return them to original position, wherein certain of the discs are variably cut away to render the action of the bar thereon variable.

4. A printing device consisting of a plurality 75

of revolubly mounted discs having printing type at their lower peripheries and having levers for setting the type in desired position, a spring actuated pressure plate, means operable by a handle for releasing the plate against the positioned type, and a bar simultaneously operable by the handle to engage the discs to return them to orig-

inal position, certain of the discs having portions cut away whereby engagement of the bar therewith on each operation of the handle is less than the engagement of the bar with others of the discs.

EDWIN KIRK LARGE.
